DESIGN FOR A TOY GUN

Irving G. Rubin, Bronx, N. Y., assignor to John C. Doig and Joseph L. Schilling, doing business as J. L. Schilling Co., New York, N. Y.

Application October 12, 1944, Serial No. 115,741

Term of patent 7 years

(Cl. D34—15)

To all whom it may concern:

Be it known that I, Irving G. Rubin, a citizen of the United States and a resident of 911 Walton Avenue, Borough of Bronx, county of Bronx, and State of New York, have invented a new, original, and ornamental Design for Toy Guns, of which the following is a specification, reference being had to the accompanying drawing, forming a part thereof.

Fig. 1 is a top plan view of a toy gun showing my new design;

Fig. 2 is a side elevational view; and

Fig. 3 is a rear elevational view thereof.

I claim:

The ornamental design for a toy gun, substantially as shown.

IRVING G. RUBIN.
